CLOSURE CAP

Richard H. Whitehead, New Haven, Conn.

Application December 11, 1934, Serial No. 756,910

6 Claims. (Cl. 215—74)

This invention relates to closure-caps, and more particularly to closure-caps for bottles and the like.

One object of this invention is to provide an improved closure-member adapted to be actuated to provide an amply-large pouring-aperture.

Another object of this invention is to provide an improved closure-cap which can be readily sealed against unauthorized opening.

10 Another object of this invention is to provide an improved closure-cap formed of simple elements, readily manufactured and readily assembled to produce an attractive, efficient and durable construction.

15 With the above and other objects in view, this invention includes all improvements over the prior art which are disclosed in this application.

In the accompanying drawing, in which one way of carrying out the invention is shown for 20 illustrative purposes:

Fig. 1 is an elevation of the top of a bottle provided with a closure-cap made in accordance with this invention;

Fig. 2 is a plan view of Fig. 1;

25 Fig. 3 is a sectional view on a plane indicated by line 3—3 of Fig. 2;

Fig. 4 is a sectional view on a plane indicated by line 4—4 of Fig. 1;

30 Fig. 5 is a sectional view on a plane indicated by line 5—5 of Fig. 3, with the closure-member in closed position;

Fig. 6 is a view similar to Fig. 5, but with the closure-member in open position;

35 Fig. 7 is a perspective view of the body of the closure-cap;

Fig. 8 is a perspective view of the operating-member; and

Fig. 9 is a perspective view of the closure-member.

40 In the description and claims, the various parts are identified by specific names for convenience, but they are intended to be as generic in their application as the prior art will permit.

The body 10 of the closure-cap is preferably 45 formed of metal and is secured to the rim or flange 11 of the bottle 12 by having the annular flange 13 of the body 10 flow-pressed into gripping engagement with the rim or flange 11 of the bottle, as shown in Figs. 3 and 4. If desired, a

50 disk 14 of cork or other suitable packing material may be interposed between the top 15 of the bottle and the lower face 16 of the body 10, to render the connection liquid-tight, and also avoid breaking the bottle. If desired, a packing-disk 55 or washer 17 of cork or other suitable material

may be cemented against the upper face or seat 18 of the body.

The operating-member 19 is preferably formed of metal and has the lower portion of the annular flange 20 flow-pressed inward to engage the 5 annular reduced portion 21 of the body so as to hold the body 10 and operating-member 19 in assembled relation, but to permit their free rotation relative to each other through a limited angle of rotation.

The body 10 has upstanding portions 22 and 23, which serve to hold the lower face 24 of the operating-member 19 spaced above the washer 17 to provide room for a closure-member 25. The closure-member 25 is preferably formed of 15 metal and has a downwardly-extending pin or stud 26 secured thereto and adapted to slidably engage in a guide-slot 27 in the body 10. The positional relation of the slot 27 is indicated by broken lines in Fig. 5, although this slot is 20 not, actually present in the parts shown in this figure. The closure-member 25 also has secured thereto an upwardly-extending pin or stud 28 adapted to slidably engage in a guide-slot 29 in the operating-member 19. The body 10 and operating-member 19 respectively have substantially-aligned apertures 30 and 31 adapted to form a pouring-opening 32. When the operating-member 19 is rotated clockwise (looking toward the top of the operating-member), or anti-clockwise (looking at Figs. 5 and 6), the slots 27 and 29, acting upon the pins 26 and 28, cause the closure-member 25 to be moved from the position indicated in Fig. 6 to that shown in Fig. 5 to bring the closure-portion 33 across the pouring-opening 32 and to project the ear-portion 34 out through a slot 35 in the side surface or flange 20 of the operating-member 19 to bring the aperture 36 in substantial alignment with the aperture 37 of the ear 38 formed on the 40 side of the operating-member (Figs. 1 and 3). The movement of the ear 34 out through the slot 35 may be limited in any suitable way, as, for example, by the edge of the ear engaging one or both of the side edges of the slot 35. If desired, a wire 39 may be passed through the openings 36 and 37 and provided with a seal 40.

When the operating member is rotated clockwise from the position shown in Fig. 5 to that shown in Fig. 6, the slots 27 and 29 50 actuate pins 26 and 28 to move the closure-member 25 to project the portion 41 of the closure-member 25 out through a slot 42 in the side-surface or flange 20 of the operating-member 19, and to bring the aperture 43 of the 55

closure-member 25 into substantial alignment with the apertures 30 and 31 to clear the pouring-opening 32. The movement of portion 41 out through slot 42 may be limited by the edge 5 of portion 41 engaging one or both of the side-edges of slot 42 or otherwise. The yieldable washer 17 aids in easily maintaining a liquid-tight closure with small friction between the washer 17 and closure-member 25.

10 It will be observed that by providing the slots 35 and 42 in the flange of the operating-member, this construction permits of a large degree of travel of the closure-member 25 and therefore a large pouring-opening, while at the same time 15 providing an attractive, efficient construction, whereby the closure-member may be sealed.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to 25 be embraced therein.

I claim:

1. A closure-cap including: a body having an aperture extending therethrough; an operating-member rotatably mounted on said body and 30 having an aperture therethrough in substantial alignment with the aperture through said body; and a closure-member between said body and said operating-member and adapted when said operating-member is rotated in one direction to close the opening formed by said aligned apertures, and when said operating-member is rotated in the opposite direction to open said opening and project a portion of said closure-member beyond the side-surface of said operating-member 35 beyond the side-surface of said operating-member, said portion, when the closure-member is in closed position, serving to aid in preventing leakage from said opening.

2. A closure-cap including: a body having an aperture extending therethrough; an operating-member rotatably mounted on said body and 45 having an aperture therethrough in substantial alignment with the aperture through said body and also having an apertured ear; and a closure-member having an apertured ear and located between said body and said operating-member and adapted when said operating-member is rotated in one direction to close the opening formed by said aligned aperture and bring the apertures of said ears in register with each other, and 50 when said operating-member is rotated in the opposite direction to open said opening.

3. A closure-cap including: a body having an aperture extending therethrough; an operating-member rotatably mounted on said body and 55 having an aperture therethrough in substantial alignment with the aperture through said body and also having an apertured ear; and a closure-member having an apertured ear and located between said body and said operating-member

and adapted when said operating-member is rotated in one direction to close the opening formed by said aligned aperture and bring the apertures of said ears in register with each other, and when said operating-member is rotated in the opposite direction to open said opening and project a portion of said closure-member beyond the side-surface of said operating-member. 5

4. A closure-cap including: a body having an aperture extending therethrough; and a flange 10 provided with a slot therethrough, an operating-member having a flange rotatably connected with said body, and provided with a slot therethrough, said operating-member having an aperture therethrough in substantial alignment with 15 the aperture through said body; and a closure-member between said body and said operating-member and adapted when said operating-member is rotated in one direction, to close the opening formed by said aligned apertures, and when 20 said operating-member is rotated in the opposite direction to open said opening and project a portion of said closure-member through said slots and in interlocking engagement with said flanges. 25

5. A closure-cap including: a body having an aperture extending therethrough; an operating-member having a flange rotatably connected with said body, said operating-member having an aperture therethrough in substantial alignment 30 with the aperture through said body and also having an apertured ear, said flange having a slot therethrough; and a closure-member having an apertured ear and located between said body and said operating-member and adapted when 35 said operating-member is rotated in one direction, to close the opening formed by said aligned apertures and project the apertured ear of said closure-member through said slot and bring the apertures of said ears in register with each other, 40 and when said operating-member is rotated in the opposite direction to open said opening.

6. A closure-cap including: a body having an aperture extending therethrough and a flange provided with a pair of slots therethrough; an 45 operating-member having a flange rotatably connected with said body and provided with a pair of slots therethrough, said operating-member having an aperture therethrough in substantial alignment with the aperture through 50 said body; and a closure-member between said body and said operating-member and adapted when said operating-member is rotated in one direction, to close the opening formed by said aligned apertures and project one portion of said 55 closure-member through one slot of each pair of slots and in interlocking engagement with said flanges, and when said operating-member is rotated in the opposite direction to open said opening and project a second portion of said 60 closure-member through the other slot of each pair of slots and in interlocking engagement with said flanges.

RICHARD H. WHITEHEAD.
